OSCILLATOR CIRCUITS

Winfield R. Koch, Haddonfield, N. J., assignor to
 Radio Corporation of America, a corporation of
 Delaware

Application June 15, 1942, Serial No. 447,008

4 Claims. (Cl. 250—20)

My present invention relates to oscillator circuits of the dynatron type, and more particularly to two-terminal circuit oscillators which can be readily synchronized with an applied voltage.

As is well known to those skilled in the art, the early screen grid tubes exhibited a negative resistance in the screen circuit by virtue of the phenomenon of secondary emission. Such a screen grid tube circuit usually had its plate at a lower positive potential than the screen grid, and the circuit was known as a dynatron circuit. Such dynatron circuits were particularly employed to produce oscillators of high frequency. I have found that a similar characteristic can be secured with a tube of the pentagrid type. In this type of tube there are usually located five control grids between the cathode and anode; the middle grid being located between a pair of positive shielding grids.

It may, therefore, be stated that it is one of the main objects of my present invention to utilize a pentagrid type of tube in a controlled dynatron oscillator circuit.

Another object of the invention is to employ the third, or middle, grid of a pentagrid tube in the negative resistance circuit, and, because of the screening action provided by the second grid relative to the cathode, to control oscillations at radio frequency without undesirable capacity coupling.

Another important object of the invention is to utilize a pentagrid tube, connected as a two-terminal oscillator, in a frequency divider network of a frequency modulated carrier wave receiver.

Yet another object of the invention is to provide an electron oscillator utilizing a pentagrid type of tube whose middle grid has connected to it the resonant oscillator tank circuit, while the grid adjacent the cathode has supplied to it modulation signals.

Still other objects of the invention are to improve generally controlled dynatron oscillator circuits, and more especially to provide oscillator circuits of the dynatron type which are not only reliable and efficient in operation, but are economically manufactured and assembled.

The novel features which I believe to be characteristic of my invention are set forth with particularity in the appended claims; the invention itself, however, as to both its organization and method of operation will best be understood by reference to the following description taken in connection with the drawing in which I have indicated diagrammatically several circuit organizations whereby my invention may be carried into effect.

In the drawing:

Fig. 1 shows a dynatron oscillator circuit embodying the invention,

Fig. 2 illustrates the characteristic secured at the middle grid of the oscillator tube of Fig. 1,

Fig. 3 illustrates another use of the invention in a frequency modulation receiver.

5 Referring to Fig. 1, the tube T schematically designates a pentagrid type of tube of the 6SA7 class. This type of tube comprises an electron emission electrode, such as a cathode K, and the anode electrode 6. In the electron stream flowing from cathode K to anode 6 there are located five control grids arranged in succession. Consider, first, that the control grid 1 immediately adjacent the cathode is connected directly to the grounded cathode. The effect of the audio modulation source S will be considered at a later point. Grids 2 and 4 are connected together to a potential point which may have a potential of approximately plus 100 volts. The direct current source for energizing the electrodes of the tube 20 is omitted for the sake of simplicity.

The middle, or third, grid 3 is located between the positive electrodes 2 and 4. The grid 3 is connected to the high alternating potential side of the resonant circuit 7 which is tuned to the operating high frequency of the system. The circuit 7 has its low potential side connected to a point of positive potential of approximately plus 30 volts, the low side of circuit 7 being bypassed to ground for high frequency currents. It will be understood that circuit 7 exhibits the negative resistance of the oscillator circuit. The tank circuit 7 may be tuned to an intermediate frequency, a radio frequency, or an ultra-high frequency in the megacycle range.

35 The grid 5 adjacent the anode 6 is shown as grounded. It will be understood that grids 2 and 4 provide an electrostatic shielding field around the intermediate grid 3. The anode 6 is connected to the plus 100 volts potential point. Still 40 assuming that the modulation source S is not in circuit with grid 1, Fig. 2 shows the characteristic of the intermediate grid in the circuit of Fig. 1.

The characteristic of Fig. 2 is secured by plotting the direct current potential of grid 3 against direct current flow in the circuit connected to grid 3. It will be observed that the characteristic includes a substantial negative resistance portion. According to my present invention, the circuit of Fig. 1 is operated so as to have the circuit 7 connected to grid 3 exhibit the negative resistance as indicated by the characteristic curve of Fig. 2. It will be seen that unlike the earlier dynatron circuits of the screen grid type, the intermediate grid is at a lower positive potential than the plate of the tube. The plate in this case is at the same, or more positive, potential than the screen, but the electrode exhibiting the negative resistance is in each case less positive 55 than the screen. In the present circuit, emitted 60

electrons are drawn to either the preceding electrode, grid 2, or to the following electrode, grid 4, instead of to only the preceding grid as in previous circuits. This results in better distribution of the heat loss of the electrodes and in a lower negative resistance, which will produce oscillations with circuits of lower dynamic resistance.

By applying audio modulation signals to grid 1, amplitude modulation of the radio frequency oscillations produced in circuit 7 may be secured. The modulated radio frequency energy could be taken from the tuned circuit through suitable coupling impedances. It could also be taken from the plate, screen, or cathode circuits by inserting a coil or resistor to give a voltage drop which can be applied to the utilization circuit. The particular advantages of the modulator of Fig. 1 are the simple tuned circuit without ticklers, taps, etc., and resulting good stability.

In Fig. 3 I have shown another use for the present invention. The controlled dynatron oscillator is here employed as a frequency divider of the type disclosed by G. L. Beers in his application Serial No. 430,588, filed February 12, 1942. The frequency divider in that application is employed in a frequency modulated carrier wave (FM) receiver. The frequency divider in the Beers application is an oscillator fed by the intermediate frequency (I. F.) network of a superheterodyne receiver, the oscillator operating at a sub-multiple harmonic and being adapted to be locked in with the applied I. F. signal energy. The function of the oscillator is to reduce the mean, or mid-band, frequency of the applied I. F. energy to a frequency value which is substantially lower than the mean frequency of the applied I. F. energy. Concurrently, the frequency deviation range of the applied I. F. energy is reduced proportionately with the reduction of the mean frequency value. In the Beers circuit a four-terminal oscillator circuit is utilized. By employing my present invention it is possible to secure the same result with a two-terminal oscillator circuit with resulting economy in cost of receiver construction.

Considering Fig. 3, the numeral 10 denotes the locked-in oscillator tube of the pentagrid type. The cathode 11 is grounded. The middle, or intermediate, grid 12 is connected to a source of plus 30 volts through the coil 13 of the resonant circuit 14. The second and fourth grids are again connected in common to the plus 100 volts potential point, and the anode 15 is similarly connected to that positive potential point. The first grid 16 is connected to the high potential side of the resonant secondary circuit 17 of the I. F. input transformer 18. The resonant primary circuit 19 of transformer 18 is arranged in the plate circuit of a preceding I. F. amplifier. The low potential side of secondary circuit 17 is connected to ground by a resistor 20 which is bypassed for I. F. currents. Direct current voltage developed across resistor 20 is utilized for automatic volume control (AVC), and the AVC lead 21, which includes the usual filter resistor, is employed for feeding the AVC bias to the signal grids of the prior signal transmission tubes.

Immediately above the transformer 18 I have depicted the type of response characteristic which is ideally desired of the I. F. transformer. It will be observed that the symbol F_c is given a value of 4.3 megacycles (mc.). This signifies that the mean, or center, frequency of the I. F. energy at transformer 18 has a value of 4.3 mc. The

transformer has a pass band width of approximately 150 kilocycles (kc.). In this way the transformer is able efficiently to pass frequency deviation up to 75 kc. on either side of the F_c value. The circuit 14 is tuned to a mean, or center, frequency of 860 kc. The pass band width of circuit 14 need only be 30 kc., since the action of the oscillator circuit is concurrently to reduce F_c and the frequency deviation range by the same proportionate integer. This action has been explained in detail in the aforesaid Beers application, and it is not believed necessary to describe it in detail in this application. The action of the locked-in oscillator is to frequency divide the applied FM energy; proportionately reduce the frequency deviation range; and also secure limiting of any amplitude modulation effects which may exist on the FM wave energy.

The FM wave energy developed across circuit 14 may be applied to any well known form of discriminator-rectifier network. For example, the circuit 14 may be the primary circuit of the well known discriminator-rectifier disclosed by S. W. Seeley in his U. S. Patent 2,121,103, granted June 21, 1938. On the other hand there may be employed a discriminator-rectifier network of the type disclosed in the aforesaid Beers application. The function of the discriminator-rectifier network is to derive the audio modulation signals from the FM wave energy developed across resistor circuit 14.

Comparing the locked-in oscillator of Fig. 3 with the generalized modulation circuit shown in Fig. 1, it will be seen that the FM energy applied to grid 16 in Fig. 3 functions as the applied controlling voltage, whereas the negative resistance effect is secured in circuit 14 connected to grid 12. Here the negative resistance presented by the tube is applied across the resonant input circuit 14 of the following discriminator network. Oscillations at approximately the center frequency of the discriminator will result, if the impedance of the discriminator is higher than the negative resistance of the tube.

Since the electron stream causing the secondary emission from grid 12 is controlled by the voltage of grid 16, the FM wave energy applied to the grid 16 will be very effective in locking in the oscillations, or in keeping them in step with the signal energy as it is frequency modulated. It will be noted that circuit 14 is tuned to a sub-multiple harmonic of the applied FM signal frequency, and that the FM wave energy is controlled at a sub-multiple harmonic by the applied signal energy. With the ordinary type of oscillator, which requires a tickler coil, another tuned circuit is required ahead of the discriminator network for the tickler to couple to. However, by using the present invention the extra tuned circuit can be omitted with resulting savings in the cost of the receiver.

The grid 12 exhibits a negative resistance which causes oscillations at the frequency of the tuned circuit, or one-fifth that of the applied I. F. signal. Due to the self-biasing action of the input grid circuit, current will flow through grid 16 only during the most positive portions of the applied I. F. signal waves. Therefore, the negative resistance of grid 12 will be obtained during five small portions of each 860 kc. oscillation. The phase of the current pulses, when the applied frequency is exactly five times the natural frequency of oscillations of the tuned circuit, will bear a definite relation to the phase of the currents in the tuned circuit. If the applied fre-

quency differs from five times the natural frequency of the circuit, the phase of the current of grid 12 will be shifted somewhat from this phase relation to the currents in the oscillating circuit. This change in phase of the current has the same effect as changing the reactance across the tuned circuit, causing it to tend to shift in frequency in such a direction that over a limited range the oscillations of the tuned circuit will always be maintained at exactly one-fifth the frequency applied. That is, the current from the grid becomes effectively reactive as well as resistive, thus changing the frequency.

Instead of a simple tuned circuit connected to grid 12, the discriminator circuit may be used. This type of circuit may exhibit a high resistance over a broader band of frequencies than a single tuned circuit. In addition, the reactance offered to the grid 12 may change much less with frequency than that of a single tuned circuit in the region of oscillations. In fact, the reactance vs. frequency curve may slope in the opposite direction from that of single circuit, depending on the coupling and damping of the circuits. It is easily seen, therefore, that in order to secure lock-in over a definite frequency range, the reactance of the discriminator circuit should be small throughout the range, so that the reactive component of the grid current in grid 12 will have a controlling effect.

Since the locally generated oscillations are always a sub-multiple of the applied I. F. signal, a given percentage change in frequency of the applied I. F. signal will result in the same percentage change in frequency of the generated oscillations. That is, when the applied I. F. signal is $4,300 + 75 = 4375$ kc., the locked-in oscillator will be $4375 \div 5 = 875 = 860 \div 15$ kc. The deviation in each case is 1.75%, but the 75 kc. deviation has been reduced to 15 kc. deviation.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In an oscillator circuit of the dynatron type, a tube provided with an electron emission electrode, a plate electrode, a control grid located in the electron stream of said tube between said emission electrode and plate, a resonant output circuit tuned to a desired high frequency, means for connecting said grid to said resonant circuit whereby said grid acts as the output electrode of the circuit, means for establishing said grid at a positive direct current potential, means for establishing said plate electrode at a substantially higher positive direct current potential, a second control grid located between said emission electrode and said first grid for providing an electrostatic shielding field, means for establishing said second grid at a positive potential which is higher than the potential of said first grid, a third grid located between the emission electrode and said second grid, a source of frequency modulated carrier wave energy connected to said third grid, said resonant circuit connected to the first grid being tuned to a sub-multiple harmonic frequency of the mean frequency of said frequency modulation energy and

a wave energy utilizing circuit coupled to solely said resonant circuit.

2. In a frequency divider network, a tube provided with an electron emission electrode, plate electrode, a control grid located in the electron stream of said tube between said emission electrode and plate, a resonant output circuit tuned to a desired high frequency, means for connecting said grid to said resonant circuit whereby said grid acts as the output electrode of the circuit, means for establishing said grid at a positive potential, means for establishing said plate electrode at a substantially higher positive potential, an input grid located between the emission electrode and said control grid, a source of angular velocity-modulated carrier wave energy connected to said input grid, said resonant circuit connected to the control grid being tuned to a sub-multiple harmonic frequency of the center frequency of said modulated carrier energy and a modulated wave energy utilization circuit coupled to solely said resonant circuit.

3. In a frequency modulation receiver, a frequency divider of the dynatron type comprising a tube provided with an electron emission electrode, a plate electrode, a control grid located in the electron stream of said tube between said emission electrode and plate, a resonant circuit output, means for connecting said grid to said resonant circuit whereby said grid acts as the output electrode, means for establishing said grid at a positive potential, means for establishing said plate electrode at a substantially higher positive potential, a second control grid located between said emission electrode and said first grid for providing an electrostatic shielding field, and means for establishing said second grid at a positive potential which is higher than the potential of said first grid, a third grid located between the emission electrode and said second grid, a source of frequency modulated carrier wave energy connected to said third grid, said resonant circuit connected to the first grid being tuned to a sub-multiple harmonic frequency of the center frequency of said frequency modulation energy and a modulated wave energy utilizing circuit connected to solely said resonant circuit.

4. In a frequency divider network, a tube provided with an electron emission electrode, a plate electrode, a control grid located in the electron stream of said tube between said emission electrode and plate, a resonant output circuit tuned to a desired high frequency, means for connecting said grid to said resonant circuit whereby said grid functions as the output electrode of the divider network, means for establishing said grid at a positive potential, means for establishing said plate electrode at a substantially higher positive potential, said plate electrode being free of any high frequency circuit, an input grid located between the emission electrode and said control grid, a source of angular velocity-modulated carrier wave energy connected to said input grid, said resonant output circuit connected to the control grid being tuned to a sub-multiple harmonic frequency of the center frequency of said modulated carrier energy, and said source being a resonant input circuit tuned to said center frequency and having a pass band substantially wider than the pass band of the resonant output circuit.

WINFIELD R. KOCH.
